ASHTRAY FOR SMOKERS

Irwin E. Cohn, New York, N. Y.

Application June 21, 1939, Serial No. 280,288

2 Claims. (Cl. 131—232)

The object of the present invention is to provide an ashtray for smokers which will incorporate simple means for effecting rotation of a pipe reamer mounted centrally within the tray, the tray in other respects being so formed as to bring the operating parts within the restricted area and form of an ashtray having generally the appearance of ashtrays which have been found most suited for the purpose and have become popular.

The invention will be described with reference to the accompanying drawing, in which—

Figure 1 is a top plan view showing certain elements in dotted lines.

Figure 2 is a vertical section on the line 2—2, Figure 1, parts being shown in elevation.

Figure 3 is a fragmentary sectional elevation showing a modified form of thumb abutment and cigar holder.

Figure 4 is a fragmentary view in elevation taken on the line 4—4, Figure 2.

Referring to the drawing, it will be seen that the tray comprises a primary ring-shaped member 1 having a rolled or beaded edge, and a centrally disposed upwardly extending flange 2 providing a chamber at 3 for containing the operative mechanism.

Chamber 3 is closed by a bottom plate 4 which may be provided with felt disks 5. In the present embodiment the top of chamber 3 is closed by a plate 6 held in position by the rivets 7, plate 6 being formed with an upwardly projecting apertured boss 6x which provides a bearing member for a shaft 8.

Shaft 8 at its top carries a reamer 9, and the depending end of the shaft has fixed thereto the hub of a pinion 10. In mesh with pinion 10 is a segment 11 pivoted upon a stud 12 carried by plate 6. Also pivoted upon stud 12 is a finger lever 13, the inner flat end of the lever lying immediately under the segment and being held immovably with respect thereto by means of pin 14. Pin 14 at its lower end is engaged by a spring 15, the opposite end of the spring being fixed to member 2 of the tray, the action of the spring being to normally hold the finger lever 13 in the position illustrated in Figure 1.

Carried by the tray in spaced relation to finger lever 13 is a thumb rest 16. In the modified form of thumb rest 16 as shown in Figure 3, the upper area of the rest is reversely bent and extends

over into the tray at 16x as a holder for cigars or cigarettes.

Plate 6 may be formed with suitably shaped depressions as at 6xx affording seats for the bowls of smokers' pipes.

When the thumb of the operator is placed on the thumb rest 16 the forefinger or fingers may be moved to operate lever 13 and effect rotation to the reamer 9 with the pipe bowl held inverted and its interior surface held in register with the reamer. The ash from the pipe bowl will be discharged within the tray.

By reason of the form of assembly the operating parts are brought within the restricted area of a tray of normal size, the operating mechanism and tray parts are inexpensive and capable of rapid assembly, so that the device will have a low manufacturing and sales cost, and, at the same time, the device will have strength and durability.

Having described my invention, what I claim and desire to secure by Letters Patent, is as follows:

1. An ash tray for smokers having a ring-shaped peripheral area with an upwardly flaring outer wall and an upwardly flaring inner wall, a horizontal top plate for the inner wall, a chamber being provided within the inner wall, the chamber being covered by said top plate, a shaft extended through said top plate, a reamer carried by the upper end of said shaft, a pinion carried by the lower end of said shaft below the plate, a segment engaging the pinion, a pivot stud for said segment, a lever connected to the segment and extending from below the peripheral area of the tray to a point laterally thereof, a thumb piece fixed to the tray in spaced relationship to the projecting end of the lever, and spring tension means applied to the lever.

2. An ash tray for smokers constructed in accordance with claim 1, in which the plate carried by the inner upwardly projecting wall of the tray is formed with a bearing boss for the reamer shaft, and with article-holding channelways extending radially from said bearing boss, and a plate removably held by the tray below the chamber covered by the plate carrying the bearing boss.
